(57) **CLAIM**

The ornamental design for a portable electric fan, as shown and described.

DESCRIPTION

FIG. 1 is a perspective view of the portable electric fan.

FIG. 2 is the front view of the portable electric fan.

FIG. 3 is a side view of the portable electric fan.

FIG. 4 is the rear view of the portable electric fan.

FIG. 5 is the side view (opposite the side view of FIG. 3) of the portable electric fan.

FIG. 6 is the top plan view of the portable electric fan.

FIG. 7 is the bottom plan view of the portable electric fan; and,

FIG. 8 is a perspective view of an alternative embodiment view of the portable electric fan.

The broken line showing of environmental structure in FIGS. 1-8 is for illustrative purposes only and forms no part of the claimed design.
